UNITED STATES PATENT OFFICE.

HERMAN VEISER, OF PHILADELPHIA, PENNSYLVANIA.

WINDOW.

1,079,525.

Specification of Letters Patent. Patented Nov. 25, 1913.

Application filed April 21, 1913. Serial No. 769,649.

To all whom it may concern:

Be it known that I, HERMAN VEISER, a subject of the Emperor of Austria-Hungary, residing at Philadelphia, in the county of 5 Philadelphia and State of Pennsylvania, have invented certain new and useful Improvements in Windows, of which the following is a specification.

My invention relates to improvements in 10 windows, the object of the invention being to provide improved mounting for window sashes, and an improved sash pocket into which both of the sashes are adapted to be moved and automatically covered or partially 15 covered by a spring-pressed sash pocket cover which constitutes a water shed to protect the pocket and bear against the lower sash when the sashes are in normal closed position.

20 A further object is to provide an improved construction of window frame in which improved sashes are mounted to slide balanced by weights in the weight boxes of the sash and locked at various positions of 25 vertical adjustment, so that the sashes may be locked either in closed or partially open position.

With these and other objects in view, the 30 invention consists in certain novel features of construction and combinations and arrangements of parts as will be more fully hereinafter described and pointed out in the claims.

In the accompanying drawings: Figure 1 35 is a perspective view of the inside of the window frame and sashes illustrating my improvements. Fig. 2 is a view in vertical longitudinal section on the line 2—2 of Fig. 1. Fig. 3 is a perspective view of the 40 outside of the window frame and sashes. Fig. 4 is a view in vertical section on an enlarged scale through the sash pocket showing both sashes in the pocket. Fig. 5 is a 45 view in cross section on the line 5—5 of Fig. 1. Fig. 6 is an end elevation of one of the sashes. Fig. 7 is a fragmentary top plan view of one of the sashes. Fig. 8 is a view in rear elevation of the sash pocket cover, and Fig. 9 is a view in section on an enlarged section through one of the sash holding devices.

1, 1, represent weight boxes connected at

the top by a horizontal bar 2, and at their lower ends by a sash pocket 3, the upper end of the latter constituting a sill 4, and said boxes 1, bar 2, and pocket 3 form a rectangular window opening in which an upper sash 5 and a lower sash 6 are mounted to slide between angle bars 6*. Both sashes 5 and 6 comprise rectangular frames 7 in 60 which window lights 8 are hinged as shown at 9 and are normally held within the frames by pivoted fasteners 10. These hinged lights facilitate the cleaning of the windows from the inside by the arm as they may be readily 65 swung inwardly and easily washed on both sides. The sashes are each connected by cords 11 with weights 12 in the boxes 1, and said cords passed over pulleys 13, so that the weight of the sashes are balanced, and the 70 latter will be supported in any position they are moved.

Brackets 14 are secured to the window frame and limits the upward movement of the lower sash as it is to be understood that 75 the lower sash never moves higher than illustrated in Figs. 1 and 2, but to open the window, it is necessary to slide the sashes downwardly into the pocket 3. Each sash is provided at one side with a ratchet toothed 80 bar 15 with which a tooth 16 on a push bar 17 normally engages. One of these push bars is illustrated on an enlarged scale in Fig. 9, and it is to be understood that one of these push bars will be provided for each 85 sash. A coiled spring 18 in pocket 19 exerts outward pressure on the push bar, and as the inner end of the push bar is connected by a link 20 with a fixed bracket 21, an inward movement of the push bar will 90 cause the tooth 16 to move out of engagement with the ratchet teeth and allow the sash to be moved.

When in engagement with the ratchet teeth, the sash will be securely locked and by providing a bar 15 of considerable length, the sash may be locked at various positions of its adjustment. The sash pocket 3 is provided with a sash pocket cover 22 located outside of the frame and preferably composed of sheet metal. This cover 22 has a depending apron 23 on its outer end, and is disposed in an inclined position, so as to readily shed the water falling thereupon.

Upwardly turned flanges 24 at the ends of the cover slide in grooves 26 in the window frame, and springs 25 secured to the outer face of the sash pocket and projected into 5 spring gripping guides 25^a on apron 23, exert a constant inward pressure on the cover 22, pressing the same tightly against the lower bar of the lower sash when the sashes are in their normal closed position 10 as clearly shown in Fig. 2.

An upwardly projecting flange 27 is provided at the inner end of the cover 22, and metal strips 28 fixed to the cover constitute cams located adjacent to the ends of the 15 cover and in the path of movement of fingers 29 on the lower sash. As a matter of fact, the fingers 29 on the lower sash normally engage the cams 28 and form parts of rails or tracks 30 secured to the outer face of the 20 lower sash, hence when a downward pressure is applied to the lower sash, the fingers 29 engaging cams 28, will force cover 22 outwardly and allow the lower sash to slide down into the pocket 3. At the same time, 25 the tracks 30 ride against the cams 28 and provide a relatively small contacting surface reducing friction and also preventing wear of the paint on the sash. The upper sash 5 is provided with similar tracks 31 30 having curved enlargements 32 at their lower ends adapted to engage cams 28 and force the cover 22 outwardly, so that the upper sash may also be moved down into the pocket 3. When the upper sash is moved 35 far enough into the pocket 3, the springs 25 will move the cover 23 rearwardly to cover the same.

While in Fig. 4 I have illustrated the cover as limited in its movement by the sash 40 cords, it is obvious that slight modifications 45 might be made in this respect, so that the cover might be otherwise positioned, but in any event, it is the intention to have the cover move inwardly so as to protect the 50 pocket from the weather. On the upper bar of both sashes, lifts 33 are supported in countersunk plates 34. These lifts 33 are 55 illustrated as forming rings having hinged mounting at their outer edges as shown at 60 35, so that when the lifts are swung upwardly and outwardly, they will tend to force the cover 22 outwardly to permit the sashes their initial upward movement. As 65 soon as the sashes begin to move upwardly, 55 they will hold the cover 22 in its outward position. In order to facilitate the upward movement of the upper sash, which is the outer sash when in the pocket 3, the upper 70 bar of this sash is curved or rounded as 60 shown at 36.

Various slight changes might be made in the general form and arrangement of parts described without departing from my invention, and hence I do not limit myself to

the precise details set forth, but consider 65 myself at liberty to make such changes and alterations as fairly fall within the spirit and scope of the appended claims.

Having thus described my invention, what I claim as new and desire to secure by Letters Patent is:

1. The combination with a window frame having a sash pocket therein, of sashes adapted to move into said pocket, and a spring-pressed pocket cover on the outside 75 of the frame, and means on the cover engaged by the sashes to force the cover outwardly when the sashes are lowered, substantially as described.

2. The combination with a window frame 80 having a sash pocket therein, of sashes adapted to move into said pocket, a spring-pressed pocket cover on the outside of the frame, cams on said spring cover, and devices on the sashes adapted to engage the 85 cams to force the cover outwardly when the sashes are lowered, substantially as described.

3. The combination with a window frame having a sash pocket therein, of sashes 90 adapted to move into said pocket, a spring-pressed pocket cover on the outside of the frame, cams on said spring cover, devices on the sashes adapted to engage the cams to force the cover outwardly when the sashes 95 are lowered, said devices comprising tracks, and enlargements on the tracks fixed to the outer faces of the vertical members of the sashes, substantially as described.

4. The combination with a window frame 100 having a sash pocket in its lower end, two sashes mounted to slide in the frame, means on the frame limiting the upward movement 105 of the lower sash, a spring-pressed pocket cover on the outside of the frame, cams on said cover, tracks on the vertical members of both sashes, and enlargements on the tracks 110 in position to engage the cams, whereby the downward movement of both sashes moves the cover outwardly, substantially as described.

5. The combination with a window frame having a sash pocket in its lower end, of two sashes mounted to slide in the frame, a pocket cover located on the outside of the 115 frame and at the top of the pocket, said cover having a depending apron at its lower end, and an upwardly projecting flange at its inner end normally pressed against the lower sash, and means compelling the cover 120 to swing outwardly when the sashes are lowered, substantially as described.

6. The combination with a window frame having a sash pocket in its lower end, of two sashes mounted to slide in the frame, a 125 pocket cover located on the outside of the frame and at the top of the pocket, said cover having a depending apron at its lower

end, an upwardly projecting flange at its inner end normally pressed against the lower sash, cams on the cover, and devices on both sashes adapted to engage the cams and force 5 the cover outwardly when the sashes are lowered, substantially as described.

In testimony whereof I have signed my

name to this specification in the presence of two subscribing witnesses.

HERMAN VEISER.
